UNITED STATES PATENT OFFICE

WILLIAM W. HOBÉ, OF NEW YORK, N. Y.

DESIGN FOR A BUTTON OR SIMILAR ARTICLE

Application filed November 2, 1929. Serial No. 33,272. Term of patent 3½ years.

To all whom it may concern:

Be it known that WILLIAM W. HOBÉ, a citizen of the United States, and resident of New York, in the county of New York and State of New York, has invented a new, original, and ornamental Design for Button or Similar Article, of which the following is a specification, reference being had to the accompanying drawing, forming part thereof, in which—

Fig. 1 is a plan view of the button embodying my new design; and

Fig. 2 is an elevational view thereon.

I claim:

The ornamental design for a button or similar article substantially as shown.

Dated New York city, October 8th, 1929.

WILLIAM W. HOBÉ.
